DESK MODEL PENCIL SHARPENER

Robert J. Brand, Berwyn, Ill., assignor to Apsco Products, Inc., Rockford, Ill., a corporation of Illinois

Filed Feb. 10, 1964, Ser. No. 78,582

Term of patent 14 years

(Cl. D74—21)

FIG. 1 is a front perspective view of a desk model pencil sharpener embodying my new design as it appears in use, the broken line showing of a pencil being for illustrative purposes only;

FIGS. 2 and 3 are side views from opposite sides of FIG. 1;

FIG. 4 is a rear view, showing the pencil chuck in retracted position, and

FIG. 5 is a top view, again showing the pencil chuck in retracted position.

I claim:

The ornamental design for a desk model pencil sharpener, as shown and described.
